(57) **CLAIM**

The ornamental design for a digital thermometer in storage case, as shown and described.

DESCRIPTION

FIG. 1 is a top view of a first embodiment of a digital thermometer in storage case showing our new design;

FIG. 2 is a bottom view thereof;

FIG. 3 is a front view thereof;

FIG. 4 is a rear view thereof;

FIG. 5 is a right side view thereof;

FIG. 6 is a left side view thereof;

FIG. 7 is a perspective top view thereof also showing the right side; and,

FIG. 8 is a perspective top view thereof also showing the left side.

The broken lines are included for the purpose of illustrating portions of the digital thermometer in storage case and form no part of the claimed design.
